UNITED STATES PATENT OFFICE
2,382,430
NECKTIE SUPPORT
Aaron London, Brooklyn, N. Y.
Application May 6, 1943, Serial No. 485,812
1 Claim. (Cl. 24—56)

This invention relates to necktie accessories. More particularly, the invention pertains to an improved device for supporting the knot of a necktie and preventing the same from loosening.

The devices heretofore commonly employed for this purpose comprised clasps having oppositely facing jaws which were adapted to grip the wings of a collar and hold the center of the clasp firmly beneath the necktie knot. Such devices disturbed the smooth and symmetrical appearance of the collar wings, particularly when used on successive days on the same shirt. In addition, the spring jaws were usually either too stiff to be readily engaged or too flexible to maintain their grip. For these reasons, and because many men did not like their conspicuous appearance, clasps have not been well received.

Another expedient was to attach a tab to the under surface of each of the wings and to button these tabs to the collar stud. This was not favored because it could not be practiced except with specially equipped shirts and because it was difficult to secure both tabs to a collar button sewed on the collar band.

Still another expedient was to pin the collar wings together. However, this either required shirts with holes preformed in the wings, to allow passage of a pin therethrough, or the piercing of holes in the wings, and in neither case could the shirt be used without a pin.

It is, therefore, an object of the present invention to provide an extremely simple necktie knot supporting device which will prevent the knot from loosening, is easy to attach but will not fall off unintentionally, does not engage the collar wings, and is barely discernible, if at all, in operative position.

A further object of the invention is to provide a device of the character described which comprises relatively few and simple parts, is rugged in construction and inexpensive to manufacture, and will serve effectively for the purposes set forth.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claim.

In the accompanying drawing, in which is

shown one of the various possible embodiments of this invention,

Fig. 1 is a front perspective view of a necktie knot supporting device embodying my invention operatively positioned on a shirt;

Fig. 2 is a medial vertical section therethrough, and

Figs. 3 through 7 are side, top, bottom, front, and rear views, respectively, of the device apart from a shirt.

Referring now to the drawing, 10 denotes a necktie knot supporting device embodying my invention. In the instant case, said device is illustrated as being particularly constructed for supporting the slipknot 12 of a four-in-hand necktie 14 at a proper predetermined elevation. It will be understood, however, as the description proceeds, that by merely slightly modifying its contour said device may be adapted to support the knots of other types of neckties, as for example that of a bow tie.

The device essentially includes two portions which, for the sake of simplicity in construction and economy of manufacture, may be integrally formed. These two portions are the attaching or end member 16 and the supporting member 18. The attaching member comprises two parallel legs 20, 22 which are spaced from each other and connected at their bases to form a yoke. These two legs may be flat and coplanar as illustrated, although this shape is merely selected to expedite the formation of the attaching member. Alternatively other shapes and configurations may be employed, providing only that said attaching portion 18 has a slot S into which a filar button supporting stem 24 or the like can be inserted and through which said stem can pass, and a pair of members spaced apart by said slot and against which a fixed collar button 26 or the like can abut. By virtue of this construction the legs 20, 22 can be slipped behind the collar button after the collar band 28 is closed thereby. In such position the device 10 is securely anchored since the weight of the tie constantly forces the curved crotch 30, which is intermediate the legs 20, 22 against the filar stem 24. This action also biases the stem to the highest curved point of the crotch so that the device is maintained symmetric relative to the collar button.

Thus the stem 24, crotch 30, and tie 14 cooperate to prevent vertical and lateral displacement of said device. It will be noted that, as will be clear in Fig. 2, the parts are so proportioned that when the shank 24 of the collar

button is at the upper end of the slot in the end member, the head 26 of the collar button fits more or less snugly in the curved portion 32 of the device, to thereby utilize the head of the collar button as a means to prevent undue deflection of the supporting member 18 when the device is in use.

It may be mentioned that the supporting member 18 will function equally well with a removable collar stud whose metal stem corresponds to the filar stem 24 and whose button head corresponds to the collar button 26, so that hereafter where the term "collar stud" is employed it will be understood to denote either a removable or a fixed collar button.

The supporting member 18 is connected to the attaching member 16 by a reverse bend 32 integrally extending from adjacent the top of said attaching member. Said supporting member comprises an upper supporting surface 34 which may roughly negatively match the configuration of the under surface of the type of knot which is to be supported by the device. Thus, where said supporting member is to be employed for holding up the slipknot of a four-in-hand necktie, said supporting surface 34 may be upwardly concavely curved and comprise a steeply slanted almost flat portion 36 adjacent the bend 32, a slightly curved jutting fore-portion or ledge 38 which is acutely inclined to the plane of the legs 20, 22 and is almost normal thereto, and a more sharply curved intermediate portion 40.

The steeply slanted portion serves to keep the bottom rear corner of the slipknot separate from the collar band, this being considered fashionable when the knot is seen in profile. The angle which this portion makes with the plane of the legs 20, 22 can be varied in accordance with stylist demands of the moment or this portion may be omitted altogether and the intermediate portion 40 joined directly to the reverse bend 32.

Said intermediate portion serves to push the body of the knot upward and forward and thus makes the knot appear as full as desired. Accordingly, the curvature of this portion may be altered to make the knot look larger or smaller.

The foreportion 38 serves to control the angle at which the tie extends from the collar band as well as to provide the main support for the slipknot. The angle which this portion makes with the plane of the legs 20, 22 may also be varied to conform to stylist demands.

The supporting member 18 is not transversely curved since the illustrated shape suffices to properly support the tie and prevent the slipknot from loosening. However, such transverse curvature can be imparted to the supporting surface 34 to cause the same to more closely negatively match the contour of the under surface of the knot.

The forward tip 42 of the foreportion 38 is disposed substantially normally to the plane of the legs 20, 22 so as to gradually ease off the support afforded by said device. Said tip has a finger 44 which is reverted and flattened out beneath the foreportion 38 whereby to round off the tip and prevent the same from fraying the necktie.

The supporting portion may be either longer or shorter relative to the slipknot than illustrated, since it is only necessary to have a substantial portion of a knot supported thereby in order to

obtain satisfactory results. Because it is not practical to provide various devices 10 having supporting portions of a great many different lengths, I may supply a device having a length of supporting member 18 such that it is adapted to function satisfactorily with necktie knots of various sizes. Such a length is about thirteen sixteenths of an inch from the tip 42 to the legs 20, 22. It is to be understood, however, that this measurement is merely by way of example and is in no way limitative.

Where the device is to be employed with bow ties, the supporting member 18 is in general smaller. The reverse band 32 may be much sharper so that the steeply slanted portion 36 can lie relatively close and almost parallel to the supporting portion 16. The intermediate portion 40 may also have a sharper curvature and the ledge 38 be shorter.

20 The device 10 may be fabricated from any material of sufficient structural strength, as for example sheet metal or plastic. It may also be die cast. If made from plastic, the attaching portion 16 may be transparent or of a color selected to 25 blend with the shirt. Likewise the supporting portion 18 may be transparent or of a color the same as or differing from that of the attaching portion 16 and such that said supporting portion will blend with the necktie and thus remain inconspicuous.

It will thus be seen that there is provided a device in which the several objects of this invention are achieved, and which is well adapted to meet the conditions of practical use.

35 As various possible embodiments might be made of the above invention, and as various changes might be made in the embodiment above set forth, it is to be understood that all matter herein set forth or shown in the accompanying drawing is 40 to be interpreted as illustrative and not in a limiting sense.

Having thus described my invention, I claim as new and desire to secure by Letters Patent:

A necktie supporting device including a relatively rigid member of thin sheet form and of uniform width throughout its length, said element having an end member longitudinally slotted to slidably cooperate with and support the element on the shank of the collar button and hold the element in predetermined relation thereto, said element including an integral tie knot supporting means extending from the upper end of the end member as a curved portion then extending downwardly and outwardly in a substantially straight portion inclined with respect to the end member, said straight portion terminating in a forwardly curved portion from which the element is projected into a relatively elongated flat tie supporting portion substantially normal to the end member, the end of the slot being disposed between the plane of the flat tie supporting portion and the curved portion leading from the upper end of the end member, whereby when in position the collar button head is disposed substantially above the plane of the tie supporting portion and between the end member and the straight portion at the upper end of the slot to assist in preventing downward deflection of the tie supporting portion when the device is in use.
